UNITED STATES PATENT OFFICE.

WALLACE DURAND, OF NEWARK, NEW JERSEY.

DESIGN FOR A SPOON.

SPECIFICATION forming part of Design No. 23,128, dated March 20, 1894.

Application filed November 24, 1893. Serial No. 491,896. Term of patent 7 years.

To all whom it may concern:

Be it known that I, WALLACE DURAND, of Newark, Essex county, and State of New Jersey, have invented a certain new and original 5 Design for Spoons, of which the following is a specification.

I have illustrated my design in a spoon, the drawing being a front view thereof.

The shank A of the handle, is shown as 10 widened out near the bowl, and as being ornamented at its junction with the bowl by the representation of a flower B, represented as hops. At the junction of the shank proper with the handle portion are two scroll figures 15 a', a², representing the edge of a piece of thin material turned inward like a scroll. The handle portion, C, where it joins the shank portion, has scroll figures c', c², representing the edge of a thin piece of material rolled inward like a scroll. From the scroll figures c', c², extend along the edge portion of the

handle, two foliate figures c³, c⁴. Beyond these are roll beads or fillets c⁵, c⁶, having foliate portions c⁷, c⁸, and terminating in scroll figures c⁹, c¹⁰, representing the edge of a thin 25 piece of material turned inward like a scroll. Intermediate of the scroll-figures a', a² and c', c² are ball-shaped figures b', b². At the extremity is a ball like figure c¹¹.

On the handle is a representation of a scorpion.

What I claim, and desire to secure by Letters Patent, is—

The design for a spoon or like article, substantially as shown and described.

In testimony whereof I have signed my name to this specification in the presence of two subscribing witnesses.

WALLACE DURAND.
